UNITED STATES PATENT OFFICE.

HENRY E. REEVE, OF NEW YORK, N. Y.

THERMOSTAT.

1,111,236.

Specification of Letters Patent. Patented Sept. 22, 1914.

Application filed January 16, 1913. Serial No. 742,336.

To all whom it may concern:

Be it known that I, HENRY E. REEVE, a citizen of the United States of America, and residing at New York, in the county 5 of Kings and State of New York, have invented new and useful Improvements in Thermostats, of which the following is a specification.

My invention relates particularly to the 10 mechanical construction, insulation and arrangement of the parts of a thermostat suitable for use in fire alarm and sprinkler systems.

The object is to provide a simple and inexpensive construction and so far as possible 15 to avoid the difficulties of short circuiting, corrosion and mechanical injury.

In its preferred form the invention contemplates a strong base of a molded insulating material of special design which supports the circuit terminals and the thermostat contacts and a cover or shield. The terminals are supported in position somewhat spaced apart from the insulating base to 20 permit the circulation of air and increase spacing of live parts. A flange and a groove are formed at the periphery of the base to prevent moisture from running in. The flange is so shaped adjacent the terminals 25 as to prevent water from dripping down on to the terminals. The base has a central depending tapered boss having a curved wall so that any moisture condensing on the under side will flow down toward the center 30 and out. This form of boss also serves to sweep the rising air against the thermostatic elements. The shield or cover shown 35 is perforated and spaced apart from the base to allow a more perfect ventilation and is supported by posts which reinforce it. These posts preferably pass through the base and are anchored at the top in a recess 40 in the base.

Figure 1, is a side view of a thermostat 45 embodying the improvements of my invention. Fig. 2, is a side view at right angles to that of Fig. 1. Fig. 3, is a separate view of the shield. Fig. 4, is a fragmentary sectional view showing the method of anchoring the shield to the base. Fig. 5, 50 is a side view and partial section of the molded insulating base. Fig. 6, is a view of the under side of the same. Fig. 7, is a fragmentary section showing modifications of 55 the base and anchorage of a circuit terminal. Fig. 8, is a fragmentary section showing a

modification of one of the supporting posts for the shield.

The base 1 is formed of a suitable molded compound which is preferably substantially 60 fireproof, a non-conductor of electricity, waterproof and strong and effected but little, if any, by changes in temperature. The circuit terminals 2, 2 are of suitable form and adapted for connection of circuit wires. The 65 thermostat members 3, 3 are of suitable design and suitably secured to the terminals 2, 2. The shield or cover 4 is preferably of cup shape to surround and protect the thermostat members and at the same time permit 70 a free circulation of air.

Each circuit terminal is secured to the base by means of one or more studs 5 which are molded into the base when the base is made. The terminals are riveted to the 75 studs so as to effect a permanent connection and yet are spaced apart from the base to allow for the circulation of air.

The base is preferably provided with a peripheral flange 6 which extends beyond the 80 upper edge of the shield 4. Just inside of the flange 6 is a groove 7 for preventing water from running in. Over each circuit terminal as at 8 I prefer to cut away the flange 6 or a part of it so as to form inclined 85 edges and cause any water or moisture which collects above to run down the inclined edges and prevent water from dripping directly on the terminals.

The top is crowned or arched for drainage purposes. In the form shown in Fig. 7 the circuit terminal 2' is anchored in the base by a screw and nut 51 and the flange 6' is cut away at 8' over the arm of the circuit terminal.

Depending from the center of the under side of the base is a boss 9, the sides of which are curved and inclined downward and toward the center so that any moisture which condenses on the under side of the base will 90 run downward toward the center and away from the terminals. A vertical passage 10 is provided through the base and boss for the supporting screw or rod (not shown). This curved surface adjacent the thermostatic elements serves to deflect the air currents and afford better circulation and quicker action.

A shield is provided with the central opening 11 for the supporting screw and to 110 permit moisture from the boss 9 to drip out. The sides and bottom of the shield are pref-

erably perforated as at 12 and the upper edge is spaced away from the base as at 13 to permit of free circulation of air and the consequent uniform and sensitive action of 5 the thermostat parts. The shield is supported by means of a number of posts such as 14, each of which pass through slots 15 and 16 in the sides of the shield 4. The lower end of the post 14 is bent upward inside the shield at 17 to secure the post to the shield. The upper end of each post has a tongue 18 adapted to be passed through an opening 19 in the base. The upper surface of the base may be provided with a recess 20 into which the end of the tongue 18 may be bent as shown in Fig. 4 and which is adapted to receive a sealing material 21 if desired. These posts support the shield spaced apart from the base and reinforce 20 the sides so that the shield may be made of thin and relatively inexpensive material without effecting the mechanical strength necessary for protecting the parts from physical injury.

25 In the form shown in Fig. 8 the post 14 has a tang 17' bent downward and inward to engage within the shield and the upper end has a perforation 22 or a recess 23 or both for the filling material 21 which thus 30 locks the post in place.

It will be obvious that changes in details of construction may be made without departing from the spirit or scope of my invention and that certain of the features may 35 be employed and others omitted. It will further be understood that the terms employed in the claims are terms of description rather than of limitation except so far as required by the state of the prior art.

40 What I claim is:—

1. In a thermostat, an insulating base having a central boss extending downwardly and providing a wall for deflecting rising currents of air outwardly and laterally 45 across the under surface of the base, a shield secured to the base, provided with an opening in the bottom thereof to permit currents of air to rise up past the boss and open at the sides to permit the currents of air to 50 flow out laterally at the sides of the shield and thermostatic elements supported beneath the base within the shield, out of contact with the base and disposed in the path of the laterally deflected currents of air so 55 as to be influenced thereby.

2. In a thermostat, a molded insulating base having a central dependent boss integral therewith, a ventilated shield secured to the base and surrounding the dependent 60 boss and curved thermostatic members mounted on the underside of the base and out of contact therewith, the said curved thermostatic members being inclosed with-

in the ventilated shield and passing around on opposite sides of the dependent boss.

65

3. In a thermostat, an insulating base having its under surface inclined downward and inward and merging into a central dependent boss, whereby moisture on said under surface will flow over the inclined surface on and down the said boss, thermostatic members supported beneath the base and out of contact with the surface of the base, a shield carried by the base inclosing the thermostatic members and provided with 70 an opening in line with the boss to permit moisture collected on the boss to drip there-through, and circuit terminals connected to the thermostatic members out of contact with the base and extending outside the 75 shield.

70

4. In a thermostat, a molded insulating base, circuit terminals anchored therein and projecting from beneath said base, said base having an integral dependent peripheral 85 flange and a groove preventing water from running beneath the base, said flange being cut away over said terminals to divert water laterally thereof.

85

5. In a thermostat, a molded insulating 90 base, circuit terminals anchored therein, thermostatic members connected to said terminals, a ventilated shield surrounding said members but spaced apart therefrom and posts connecting said shield and said base 95 and reinforcing the side walls of said shield.

95

6. In a thermostat, a base, circuit terminals secured thereto, thermostatic members connected to said terminals, a shield surrounding said thermostatic members and a 100 number of posts connecting said shield to said base and reinforcing the sides of said shield, each post passing through said shield and having one end bent into hook shape to connect it to said shield.

105

7. In a thermostat, a base, circuit terminals secured thereto, thermostatic members connected to said terminals, a shield surrounding said thermostatic members and a number of posts connecting said shield to 110 said base and reinforcing the sides of said shield, each post passing through said shield and having one end bent into hook shape to connect it to said shield, the other end passing through the base and bent over to secure it to the base.

110

8. In a thermostat, a molded insulating base, having an integral depending peripheral flange, circuit terminals and thermostatic elements carried by and projecting 120 from beneath the under side of said base within the margin of said flange, said flange receding over said terminals to divert water laterally thereof.

120

9. In a thermostat, a base, thermostatic elements carried thereby, a shield for said

125

elements, and supporting posts for said shield passing twice through the walls of said shield and reinforcing the walls of said shield.

5 10. In a thermostat, a base, thermostatic elements carried thereby, a shield surrounding said elements, reinforcing and securing posts connected to said base, each post pass-

ing through the upper flange of said shield and having a hook portion at its lower end to hooked through said shield.
